UNITED STATES PATENT OFFICE.

BENJAMIN LAWRENCE, OF LEYTON, ENGLAND.

MAGNETO IMPULSE-STARTER.

1,294,282.

Specification of Letters Patent. Patented Feb. 11, 1919.

Application filed November 12, 1918. Serial No. 262,169.

To all whom it may concern:

Be it known that I, BENJAMIN LAWRENCE, a subject of the King of England, residing in Leyton, Essex, England, have invented certain new and useful Improvements in Magneto Impulse-Starters, of which the following is a specification.

This invention relates to magneto impulse-devices for starting purposes, and a primary object is to provide an improved construction of apparatus of the kind wherein a driving-member for connection to the engine-shaft is connected to a driven-member for connection to the magneto-shaft through a spring, and a movable part of the driven-member coöperates with a stationary stop to hold the driven-member back until the spring is loaded, when the said catch is automatically tripped; the catch may further operate under centrifugal control as a positive driving-element between the driving and driven members when the starter is running at speed.

It is well-known that the object of these devices is to enable the magneto-armature to have a rapid angular movement given to it when the engine is being only slowly cranked around so that an efficient spark may be produced notwithstanding the slow movement of the engine-shaft.

In a magneto impulse-starter according to this invention, the driven-member enters the driving-member and the catch is mounted on the driven-member with its operative end projecting through a slot in the driving-member to engage a stationary stop disposed outside the circumferential sweep of the driving-member in such manner that when the catch is at one end of the slot it engages the said stop, but when the further movement of the driving-member brings the other end of the slot against the operative end of the catch the said catch is thereby disengaged from the stop.

The invention consists in the construction, arrangement and combination of parts described hereinafter and pointed out in the claims.

One embodiment of the invention is illustrated by way of example in the accompanying drawings, wherein:-

Figure 1 is a section through the apparatus in the plane of the axis of rotation;

Fig. 2 is a section taken on the line 2-2 in Fig. 1;

Fig. 3 is an elevation of the apparatus viewed from the right of Fig. 1; and

Fig. 4 is a face view of the driving and driven elements seen from the right of Fig. 1 with the outer casing removed.

Like letters indicate like parts throughout the drawings.

The driving-member A is cup-shaped, the walls A¹ forming the cup being slotted at A² and having on the non-slotted portions 65 projections A³. The member A is provided with a central tongue A⁴ whereby it can be secured to the driving-shaft. The driven-member B comprises a hub having a jaw B¹ engaging with a corresponding coupling-element on the magneto-spindle, and a flange B², the periphery of which is recessed at B³ to receive the projections A³ on the walls A¹ of the member A. The hub of the member B extends axially into the cup-shaped 75 member A and is surrounded at its end by one or more flat spiral springs C, the inner end of which is secured to the hub B and the outer end to a part C¹ fast on the inner face of the walls A¹ of the member A. At 80 the side of the spring and still within the cup-shaped member is a disk D which is fast on the hub of the member B or is held in rigid relation thereto by screws D¹ which extend through the disk D into the flange 85 B². Between the disk and flange studs D² are carried, and on each stud is mounted a catch E having an operative end E¹ and a weighted tail portion E². Sliding radially in a guide F² on the disk D are two spring-controlled detents F. These are situated on opposite sides of the boss B and engage recesses in the walls A¹ of the cup-shaped member A. Auxiliary detents F¹ free to float in their supports engage the sides of 95 the detents F and have their outwardly projecting ends in proximity to the catches E. The detents F are notched on the side toward the flange B² as also are the guides F², and bars F^{2*} lie one across each detent and 100 in the notches in the guides. The bars hold the detents in against undue displacement endwise and are themselves kept in place by the screws D¹ and the flange B².

To keep the members A and B in alignment a pin A⁴ is made fast in the member A and projects into the boss B. A set-screw B⁴ in the boss abuts against the end of the pin A⁴ and thus spaces these two members apart. The two members are thus inclosed 110

in a casing G, G¹, G² comprising a main body-portion G having a foot G¹, whereby the whole mechanism can be secured to a suitable support, and a detachable plate G².

5 Ball-bearings G³ are provided between the main body G of the casing and the driving member A and between the detachable plate G² and the driven-member B.

In the top of the casing G is a stationary 10 stop H. This is secured in place by screws H¹ and projects through the casing into proximity to the exterior of the driving member A. One side of the projecting portion of the stop has a face H² set at such 15 an angle as to arrest the operative end E¹ of either of the catches E, and the other side of the projection has a face H³ which is so sloped that it will not arrest the catches even though the stop be turned around to bring 20 this face into the position of the face H².

The operation of this apparatus is as follows:—

As the engine-shaft, which is secured to the driving member A, is slowly turned 25 around by the crank-handle, the member A first carries with it the driven member B because of the interconnecting detents F. This movement, which is in the direction of the arrow in Fig. 2, continues until the operative end E¹ of one of the catches E is 30 brought against the face H² of the stop H. The weighted tails E² of the catches insure that when turning the handle slowly the operative ends of the catch will lie in the path 35 of the stop H. The driven member B is thus arrested, and consequently the detents, whose ends are rounded, are forced out of engagement with the wall A¹ of the driving member. The continued angular movement 40 of the member A, therefore, will now load the spring C which connects the members A and B until the end of the slot A², through which the operative end of the catch projects, is reached, when the wall A¹ of the 45 member A will strike the operative end of the catch and drive it inward so that it is released from the stop H. This tripping of the catch E¹ causes the member B to be suddenly rotated relatively to the member A by 50 means of the spring, which quick movement communicated to the magneto-spindle produces the required spark. The forward movement of the member B is arrested by the 55 projections A³ on the member A operating in the recesses B³ in the flange B², and when so arrested the detents F are once more in line with the recesses for them in the walls A¹ of the member A, so that they once more drop into position. The apparatus is thus 60 ready for a second effort or, if the engine has started, immediate increase of speed causes the weighted ends of the catches E to fly out so that their operative ends E¹ are carried inward and out of the path of 65 the stationary stop H. The drive between

the engine-shaft and the magneto is now maintained through the spring or springs C and the detents F.

It is not desirable to drive through the yielding control-spring C only at any time, 70 and therefore it is necessary to insure that the engagement of the detents shall be sufficient to keep the driving and driven parts interlocked. Lest therefore they should jerk out of place, the auxiliary detents F¹ 75 are provided; these act ordinarily merely as floating pins between the detents F and the catches E, being easily brushed aside when the detents F are forced back, but they can no longer float when the catches are moved 80 in by centrifugal force, as the catches then abut against the ends of these pins and hold them in against displacement.

The beveled face H³ on the stop H assists the passing of the catches E if the engine-shaft is at any time turned in the wrong direction, but it is also provided for throwing the device out of action, as by reversing the lock, that is turning the stop through an angle of 180°, so that when the face H³ is 90 brought to the position occupied by the face H² the catches are prevented from being arrested by the stop. Throwing the device out of action could also be effected by making this stop adjustable radially. 95

Instead of the auxiliary detents F¹ the tail ends of the catches may be so shaped that when they swing outward they engage co-operating recesses in the driving member A and these operate as pawls, whereby a positive drive is effected, springs being provided to move the catches out from this locking position when the speed is reduced. 100

It will be seen that the same weighting of the tail-ends of the catches which serves 105 to bring their operative ends out of the path of the stop at high speeds, serves to bring them into the path of the stop at low speeds.

It will be appreciated that when the magneto impulse-starter is arranged as described and illustrated, it constitutes a self-contained unit which can be interposed between the engine-shaft and the magneto-spindle without difficulty, as the jaw B¹ of the member B can engage a correspondingly 110 shaped tongue on the spindle and the tongue A² on the member A can engage a correspondingly shaped jaw on the engine-shaft; the foot G¹ of the casing affords simple means whereby the device can be rigidly secured in position after connection with the engine-shaft and magneto-spindle. 115

In some cases it may be preferred to dispense with the yielding detents F and their auxiliary detents F¹, as these are not essential, because the initial movement given by the engine-shaft necessary to bring the ends E¹ of the catches into operation would still take place through the connecting springs C, and the positive drive would be effected 120 125 130

by means of the tail-ends of the catches engaging the driving-member A under centrifugal action as already described.

What I claim as my invention and desire 5 to secure by Letters Patent is:—

1. In a magneto impulse-starter of the kind described, the combination with a driving member having a slot in the periphery thereof, a driven member having a portion 10 entering axially into the driving member, and a spring operatively connecting the driving member to the driven member, of a stop fixed outside the circumferential sweep of the driving member, and a catch mounted 15 on the driven member, one operative end of the said catch normally projecting through said slot and being adapted to abut against said stop at one end of the slot when the driven member is rotated by the driving 20 member through the medium of said spring, and to be released therefrom by the other end of said slot during the further movement of the driving member.

2. In a magneto impulse-starter of the kind described, the combination with a driving member having a slot and a recess in the periphery thereof, a driven member having a portion entering axially into the driving member, and having a projection taking 30 into said recess for limiting the relative movement of said members, and a spring operatively connecting the driving member to the driven member, of a stop fixed outside the circumferential sweep of the driving member, and a catch mounted on the 35 driven member, one operative end of said catch normally projecting through said slot and being adapted to abut against said stop at one end of the slot in one angular position of the driving member and to be released therefrom by the other end of said slot in another angular position of the driving member.

3. In a magneto impulse-starter of the kind described, the combination with a driving member having a slot in the periphery thereof, a driven member having a portion entering axially into the driving member, and a spring operatively connecting the 40 driving member to the driven member, of a stop fixed outside the circumferential sweep of the driving member, a catch mounted on the driven member, one operative end of the 45 said catch normally projecting through said slot and being adapted to abut against said

stop at one end of the slot when the driven member is rotated by the driving member through the medium of said spring, and to be released therefrom by the other end of said slot during the further movement of 60 the driving member, and a spring-pressed detent guided on the driven member and normally engaging the driving member.

4. In a magneto impulse-starter of the kind described, the combination of a driving member having a slot in the periphery thereof, a driven member having a portion entering axially into the driving member, a spring operatively connecting the driving member to the driven member, a guide fixed 65 on the driven member, a spring-pressed detent guided by said guide and normally engaging the driving member, an auxiliary detent slidable in said guide and adapted to lock said spring-pressed detent in its engaging position, a stop fixed outside the circumferential sweep of the driving member, and a catch mounted on the driven member, one operative end of said catch normally projecting through said slot and being adapted to abut against said stop in one angular 70 position of the driving member and to be released therefrom in another angular position of the driving member relatively to the driven member, the said operative end of the catch in its released position being arranged to coact with the said auxiliary detent and hold the same in its locking position.

5. In a magneto impulse-starter of the kind described, the combination of a driving member having a slot in the periphery thereof, a driven member having a portion entering axially into the driving member, a spring operatively connecting the driving member 90 to the driven member, a casing surrounding said members, a stop having two opposed faces detachably and reversibly fixed in said casing outside the circumferential sweep of the driving member, and a catch mounted on the driven member, one operative end of said catch normally projecting through said slot and being adapted to abut against said stop at one end of the slot, and to be released therefrom by the other end of said slot during relative rotation of the said members.

In testimony whereof I affix my signature.

BENJAMIN LAWRENCE.
